DESIGN FOR A RANGE

William J. Russell, Mansfield, Ohio, assignor to
Westinghouse Electric & Manufacturing Com-
pany, a corporation of Pennsylvania

Application December 11, 1941, Serial No. 104,564

Term of patent 14 years

To all whom it may concern:

Be it known that I, William J. Russell, a citizen
of the United States, residing at Mansfield, in the
county of Richland and State of Ohio, have in-
vented a new, original, and ornamental Design
for a Range, of which the following is a specifica-
tion, reference being had to the accompanying
drawing, forming a part thereof.

Fig. 1 is a perspective view of a range embody-
ing my new design; and,

Fig. 2 is a fragmentary side elevational view of
the design illustrated in Fig. 1, the lower portion
of the range being broken away.

The dominant features of my design reside in
the portions shown in full lines.

I claim:
The ornamental design for a range, substan-
tially as shown.

WILLIAM J. RUSSELL.
